UNITED STATES PATENT OFFICE.

HECTOR LE DOUX, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

STOP-MOTION FOR LOOMS.

1,307,012.

Specification of Letters Patent. Patented June 17, 1919.

Application filed March 20, 1917. Serial No. 156,167.

To all whom it may concern:

Be it known that I, HECTOR LE DOUX, a citizen of the United States, residing at Worcester, in the county of Worcester and 5 State of Massachusetts, have invented a new and useful Stop-Motion for Looms, of which the following is a specification.

This invention relates to a stop motion for looms, particularly designed for use in 10 a loom having a positive shuttle motion.

It is the object of my invention to provide an improved stop motion for looms having a positive shuttle motion, which shall become operative to stop the loom whenever a 15 shuttle is not properly boxed.

With this general object in view, an important feature of my invention relates to the provision of shuttle feelers positioned to engage a shuttle at each end of its path 20 of travel, and connected to control loom-stopping mechanism.

In the double shuttle loom shown in the drawings, separate pairs of feelers are provided for the upper and lower shuttles, and 25 all of said feelers are connected to control a single loom-stopping mechanism. An additional feature of my invention relates to the provision of connections whereby a weft detector or filling fork independently controls 30 the same stopping mechanism.

Further features of my invention relate to the provision of means for periodically rendering the shuttle feelers inoperative, and to the provision of a reciprocating vibrator coöperating with a vibrator-engaging member to stop the loom whenever the weft fails or a shuttle is not properly boxed. 35

My invention further relates to certain arrangements and combinations of parts which 40 will be hereinafter described and more particularly pointed out in the appended claims.

A preferred form of my invention is shown in the drawings in which—

Figure 1 is a front elevation of a loom 45 having my improvements embodied therein;

Fig. 2 is a right-hand side elevation of the loom shown in Fig. 1;

Fig. 3 is a sectional side elevation taken along the line 3—3 in Fig. 1;

Fig. 4 is a front elevation of the devices for supporting and yieldingly positioning two of the shuttle feelers;

Fig. 5 is a right-hand elevation of the parts shown in Fig. 4;

Fig. 6 is an enlarged side elevation of the

vibrator-engaging member and the connections by which it is moved to operative position;

Fig. 7 is a top plan view of the filling fork and slide, and 60

Fig. 8 is a side elevation of the parts shown in Fig. 7.

Referring to the drawings, I have shown a double shuttle loom having shuttle boxes 10, 11, 12 and 13 adapted to receive positively-actuated shuttles 14 and 15. The mechanism for actuating the shuttles forms no part of my invention and may be of any usual type adapted to move the shuttles simultaneously in opposite directions. 70

A lay L (Fig. 1) supports a reed R and is operated to beat up the filling in the usual way. As the shuttles are continuously supported in their flight the lay omits the usual shuttle race. The operating mechanism for 75 the lay may be of any usual type and is omitted from the drawings for the sake of clearness.

A pair of shuttle feelers 16 and 17 (Figs. 2 and 3) are provided for engaging the 80 shuttle 14 at each end of its path of travel, and a second pair of feelers 18 and 19 are provided for engagement with the lower shuttle 15.

I will first describe the connections and 85 operations of the feeler 16. The feeler 16 is mounted in a hub or casting 20 (Figs. 4 and 5) which is free to turn upon a fixed stud 21 rigidly supported on the loom frame F, the hub being retained upon the stud by 90 a collar 22. The feeler 16 is yieldingly advanced into the path of the shuttle 14 by a spring 23 connected at one end to the hub 20 and at the opposite end to a collar 24 fixed in adjusted position on the stud 21. 95

A wire or rod 25 is fixed in the hub or casting 20 and extends laterally beneath a stud 26 (Fig. 2) mounted on the end of an arm 27 fast to a shaft 28 (Fig. 1) mounted in bearings in the loom frame F. A second 100 arm 30 (Figs. 2 and 6) is fixed to the shaft 28 and is link-connected to an engaging member 31 pivoted at 32 to a lever 33 mounted upon a stud 34 on the loom frame. The lever 33 is connected by a rod or link 35 to 105 loom-stopping mechanism, (not shown), the connections being so arranged that movement of the engaging member 31 toward the front of the loom will cause the stopping of the loom. 110

The member 31 is normally positioned in the path of a vibrator 40, as shown in full lines in Fig. 6. The vibrator 40 is slidable in a fixed bearing 41 (Fig. 2), and at its 5 rear end is connected to a vibrator lever 42 positioned for engagement by a rotating cam 43. The cam 43 periodically advances the vibrator 40 and the vibrator is alternately withdrawn by a spring 44 connected 10 between the vibrator lever 42 and the loom frame F.

The link which connects the arm 30 to the member 31 comprises a part 45 pivoted to the arm 30 and a rod 46 pivoted to the member 31 and slidable in bearings on the part 45. The link is normally contracted by a spring 47 interposed between a collar 48 fixed to the rod 46 and one of the bearings on the part 45. A second collar 49 fixed to the 20 rod 46 limits the contraction of the link. The arm 30 and the member 31 are thus connected in such a way that the parts can yield if the arm 30 is raised while the vibrator 40 is above the member 31.

25 When the shuttle 14 is out of the box 11, the spring 23 moves the feeler 16 into the box and at the same time through the rod 25, the arm 27, the shaft 28, the arm 30 and the link 45-46 it moves the engaging member 31 into the path of the vibrator 40.

The feeler 18 (Fig. 2) is mounted upon a stud 50 and is provided with a rod 51 extending beneath the stud 26 and the arm 27 and is similarly effective to raise the member 31 into the path of the vibrator 40 if the shuttle 15 fails to enter the box 13.

35 The feeler 17 (Fig. 3) on the left-hand side of the loom is mounted on a fixed pivot 52 and is connected by a link 53 to an arm 54 fast on a horizontal shaft 55 (Fig. 1) mounted in bearings in the loom frame F. A second arm 56 (Fig. 2) secured to the shaft 55 is connected by a link 57 to the hub or casting 20 of the feeler 16. In this 40 way the feelers 16 and 17 are connected to operate simultaneously in connection with the shuttle 14.

The feeler 19 is similarly connected through a link 60, a shaft 61 and a second 50 link 62 to the hub of the feeler 18 and the feelers 18 and 19 thus coöperate to control the shuttle 15.

With these connections it will be evident that the boxing of the shuttle 14 at either 55 side of the loom will lower the rod 25, thus permitting the engaging member 31 to move to anoperative position. Such movement, however, cannot take place unless the shuttle 16 is also properly boxed and coöperates 60 with one of the feelers 18 or 19 to lower the rod 51. Thus if the shuttles are both properly boxed the member 31 will be lowered to anoperative position, but if either shuttle is 65 out of its proper position the loom-stopping mechanism will be rendered operative.

The cam 43 which operates the vibrator 40 is rotated through the gears and pinions shown in Fig. 2, and makes several revolutions to each actuation of the shuttles 14 and 15. The vibrator 40 is thus reciprocated several times during the rather slow travel of the shuttles from one side of the loom to the other, and would stop the loom during the flight of the shuttles if provision were not made for moving the member 75 31 to inoperative position during this period.

Such provision is shown in Fig. 3, and comprises arms 63 and 64 secured to the shafts 55 and 61 respectively and connected by links 65 and 66 to a lever 67 intermittently actuated by a cam 68 which rotates once for each flight of the shuttles. The rods 65 and 66 have pin and slot connections with the lever 67, thereby providing a limited lost motion.

When the lever 67 is in the position shown in Fig. 3, the feelers are free to engage the shuttles and if the shuttles are not properly boxed they are permitted by the lost motion connections to move farther into the boxes, thereby causing the stopping of the loom. During the greater part of the revolution of the cam 68, however, the lever 67 is moved to the position shown in dotted lines, in which position it withdraws each of the feelers from its shuttle box and depresses the rods 25 and 51, thus permitting the member 31 to move to inoperative position.

I have thus provided means for separately engaging each shuttle in either shuttle box and for stopping the loom if either shuttle fails to box in one or the other of its shuttle boxes and I have further provided means for rendering the shuttle feelers inoperative during the flight of the shuttle. While the mechanism is shown and described as adapted to a double shuttle loom, it will be evident that certain features of said mechanism may be used to equal advantage in a loom having a single positively-actuated shuttle. My improved stop motion is shown herein in connection with a loom in which the shuttles are positively actuated. The particular method of actuating the shuttles is, however, immaterial, and the advantages of my invention may be fully utilized in a loom in which the shuttles are not positively actuated.

In Figs. 7 and 8 I have shown a filling fork 70 mounted in a fork slide 71 slidable in a stand 72 and connected by an arm 73 to a short shaft 74 pivoted in the loom frame F. A second arm 75 (Fig. 3) mounted on the shaft 74 is connected by a link 76 to an arm 77 secured to the shaft 28 (Fig. 1) which supports the arm 30 (Fig. 6) and controls the position of the engaging member 31. An actuator 80 (Fig. 8) is pivoted at 81 to the stand 72 and is connected by a link 82 (Fig. 3) to an arm 83 fixed to a

shaft 84 (Fig. 1) mounted in bearings 85 (Fig. 3) and 86 (Fig. 2). A cam follower 87 is secured to the shaft 84 and engages a rotating cam 88 shown in dotted lines in Fig. 2.

The actuator 80 is thus continuously vibrated and upon failure of the weft the hook of the fork 70 is engaged by the actuator, thus moving the slide 71 to the left (in Fig. 8), which movement through the connections described raises the member 31 into the path of the vibrator 40, thus stopping the loom. A spring 90 returns the filling fork slide after such engagement.

I thus provide weft detecting mechanism adapted to coöperate with the shuttle feelers and I employ a single loom-stopping mechanism for use with these two sets of control devices.

A hand stopping lever 91 is pivoted at 92 to the frame F and is connected to the lever 33 for stopping the loom manually. A spring 93 (Fig. 6) partially counterbalances the weight of the member 31 and the parts associated therewith.

Having thus described my invention, it will be evident that changes and modifications can be made therein by those skilled in the art without departing from the spirit and scope of my invention as set forth in the claims, and I do not wish to be otherwise limited to the details herein disclosed, but what I claim is:—

1. In a double shuttle loom, in combination, a pair of shuttles, actuating means therefor, separate shuttle feelers for each shuttle at each side of the loom, said feelers being connected in pairs so that the two feelers for each shuttle operate together, normally operative loom stopping mechanism, and connections from said feelers to said mechanism, each pair of feelers associated with the same shuttle being independently effective to maintain said loom stopping mechanism in operative position until a shuttle is boxed in one or the other of the shuttle boxes controlled by said pair of feelers.

2. In a double shuttle loom, in combination, a pair of shuttles, actuating means therefor, separate shuttle feelers for each shuttle at each side of the loom, and means

to stop the loom including a member normally maintained by said shuttle feelers in operative position but released by said feelers and permitted to move to inoperative position only when both shuttles are properly boxed either at the same or at opposite sides of the loom.

3. In a double shuttle loom, in combination, a pair of shuttles, actuating means therefor, separate shuttle feelers for each shuttle at each side of the loom, connections whereby the two feelers for each shuttle operate together, loom stopping mechanism, connections from each pair of feelers to said mechanism, whereby either pair of feelers may render said mechanism operative, a filling fork, connections whereby said filling fork may independently control said stopping mechanism, and means to render said shuttle feelers periodically inoperative, said filling fork control continuing operative.

4. In a double shuttle loom, in combination, a pair of shuttles, actuating means therefor, loom stopping mechanism including a member movable into and out of operative position, a pair of shuttle feelers for each shuttle, connections from each pair of feelers to said member whereby each pair of feelers is rendered independently effective to move said member to operative position, a filling fork, and additional connections from said filling fork to said member whereby said filling fork is rendered effective to independently move said member to operative position.

5. In a double shuttle loom, in combination, a pair of shuttles, actuating means therefor, a pair of shuttle feelers for each shuttle, a vibrator, a cam to actuate said vibrator, means to rotate said cam continuously, a movable vibrator-engaging member, connections through which said member when engaged by the vibrator is effective to stop the loom, and means independently controlled by each pair of shuttle feelers effective to control the movement of said member into and out of the path of said vibrator.

In testimony whereof I have hereunto affixed my signature.

HECTOR LE DOUX.
